UNITED STATES PATENT OFFICE.

JOHN JOSEPH COOPER, OF LONDON, ENGLAND, ASSIGNOR TO UNDERWOOD TYPE-WRITER COMPANY, OF NEW YORK, N. Y., A CORPORATION OF DELAWARE.

COPY-HOLDER.

1,182,459.

Specification of Letters Patent.

Patented May 9, 1916.

Application filed July 25, 1912. Serial No. 711,609.

To all whom it may concern:

Be it known that I, JOHN JOSEPH COOPER, a subject of the King of Great Britain, and resident of 120 Queen Victoria street, London, E. C., England, type-writer mechanic, have invented certain new and useful Improvements in Copy-Holders, of which the following is a specification.

My invention relates to copy holders for supporting and feeding tapes or strips having written, printed or impressed thereon telegraph messages or other copy to be transcribed.

When it has been required to transcribe, by means of a typewriting machine, telegraph messages or other matter from a considerable length of tape, inconvenience has been experienced and errors have resulted on account of the difficulty not only of holding the tape in position to be easily read by the typist, but of keeping the latter continuously supplied with the tape. The tape itself, as is well known, is as a rule of great length relatively to the space actually occupied by the written message when condensed into ordinary typewritten matter, this being more especially noticeable in cases where the tape is inscribed not with Roman or other usual characters but with Morse or other code signs requiring translation into common language.

An object of the present invention is to overcome the above-noted difficulties, and to this end the invention provides a simple means of presenting successive portions of a continuous length of telegraph tape (or similar lengthy strip of relatively narrow material) in the position most convenient for inspection by the operator, and of enabling the latter to draw the tape past what may be termed the copying position, step by step or continuously at any desired speed.

The tape containing the inscription or copy to be transcribed is led horizontally across the front of the typewriting machine above the keyboard, by being passed at one end of the machine through a stationary guide and at the other end through a guide and also between a pair of feed-rollers one of which is furnished with ratchet and pawl mechanism whereby it may be rotated at will by the typist on the latter operating a lever provided for the purpose, the tape being held in frictional contact with the pe-

riphery of this driving feed-roller by spring-pressure applied to the other roller of the pair.

The lever, by means of which the operator actuates the ratchet mechanism for rotating the driving feed-roller, may be operated either by hand or by foot. In the former case the lever would be in the form of a finger-key which would most conveniently be placed alongside of and on substantially the same level as the ordinary keys of the typewriting machine; the finger-key in question being, for example, on the front end of a lever fulcrumed toward the back of the machine, and spring-pressure being employed for returning said key-lever to its normal or raised position. Adjustable stops may be provided for limiting the movement of the key-lever in each direction, and if desired, a device may be adopted for checking the rotation of the driving feed-roller at the termination of the operative stroke of the lever. For this latter purpose the key-lever, on reaching the end of its movement, may strike a lever adapted to bring a stop-pawl into the path of teeth on the periphery of a wheel rotating concurrently with the driving feed-roller, as will be readily understood.

In place of the manually-operable arrangement just mentioned, it is as a rule preferred to employ a pedal-operated lever adapted to be depressed by the foot of the operator and returned by spring-pressure, the operator being thus relieved of the necessity of removing his hand from the ordinary keys of the keyboard in order to actuate the type-feeding mechanism. It is also preferred to utilize both the up and down movements of the pedal-operated lever or otherwise multiply the impulses of the down stroke for the purpose of actuating the ratchet-mechanism, employing for this purpose two driving pawls, both coupled to the lever and respectively caused to operatively engage the teeth of the ratchet-wheel according as the pedal is being depressed from or returned to normal position. A similar double-acting arrangement is obviously applicable also in the case of the manually-operable apparatus previously mentioned. The speed at which the web is fed forward being equal to or proportional to the peripheral speed of the driving feed-wheel, is independ-

ent of the amount of tape that has been fed through the machine, so that a more uniform speed may be maintained than is possible where the web is wound on a driving spool whose effective diameter increases with the amount of tape wound thereon.

Other objects and advantages will hereinafter appear.

In the accompanying drawings, which illustrate constructions embodying the invention, Figures 1 to 4 show one form of construction, Fig. 1 being a front elevation of portions of a typewriting machine to which the invention is applied, while Fig. 2 is a part rear elevation, and Fig. 3 a side elevation of the same. Fig. 4 is a side elevation, drawn to a smaller scale, showing the foot pedal and its connection with the ratchet-and-pawl mechanism. Fig. 5 is a rear view, similar to Fig. 2, showing a slightly modified construction.

The tape 11 containing matter to be transcribed is led horizontally across the front of the machine above the keyboard 12 in a convenient position to be seen by the operator, being passed at one side of the machine through a stationary guide 13, and at the other side through a guide 14. Beyond the guide 14 the tape is gripped between the peripheries of a pair of feed-rollers 15, 16, whereof the roller 15 is held by spring-pressure in contact with the roller 16. The roller 16, which constitutes the driving feed-roller, receives rotary motion through the medium of ratchet-and-pawl mechanism, from a lever 17 (Fig. 4) provided with a pedal 18 and mounted to oscillate about an axis 19 beneath the table 20 which supports the machine, the lever 17 being adapted to be depressed by the foot of the operator pressing upon the pedal 18 in opposition to a spring 21 whereby, after each depression the lever is returned to the normal or raised position indicated in Fig. 4.

The lever 17 operates upon the ratchet-and-pawl mechanism above referred to, through the medium of an upright connecting rod 22 whose lower end is pivotally attached at 23 to the lever while its upper end is given a substantially straight line movement by means of a pin 34 in the head of the rod, guided in a slot 35 in a guide bracket 36 substantially in a line intersecting the axle 24 of a ratchet wheel 25. The reciprocations of the rod 22 are converted into a rotary movement of the ratchet wheel 25 by means of driving pawls 26 and 27 pivoted respectively to the outer ends of arms 28 and 29 freely mounted at their inner ends on the axle 24 and extending on opposite sides of said axle, said arms being connected through links 31 and 32 to a pin 30 on the head of the rod 22. The pawls 26 and 27 are both adapted to drive the ratchet wheel in the same direction so that as long as the

rod 22 continues to reciprocate, the ratchet wheel receives a practically continuous rotation.

Fixed to the axle 24 so as to rotate with the ratchet wheel 25 is a gear wheel 41 running in mesh with a pinion 42 secured to the axle of the driving feed roller 16, the pinion 42 being preferably of smaller diameter than the gear wheel 41 to increase the length of web 11 fed at each reciprocation of the rod 22. Thus with the parts proportioned as shown in Fig. 2, the feed roller 16 will be given approximately a complete rotation for each movement of the rod 22 in either direction, although it will be understood that the ratio of the gearing may be varied as desired.

In the modification illustrated in Fig. 5, which is designed to meet conditions where a less rapid movement of the tape 11 is required, the gear wheels are omitted and the ratchet wheel 25 is mounted directly on the axis of the driving feed roller 16. In the construction shown in this figure, a pin 37 on the head of the rod 22 forms a pivotal connection with a rock arm 38 which oscillates about a stationary axis 39 on a bracket 40; the arm 38 oscillating in a plane parallel to the ratchet wheel, and the path of the pin 37 being approximately in a line 95 intersecting the axis 24 of the ratchet wheel, whereby both pawls rotate the ratchet wheel through substantially the same angle and at a speed approximately equal to that of the actuating rod 22. It will be understood that the means, shown in Fig. 5, for guiding the upper end of the rod 22, might be employed with the form of gearing illustrated in Fig. 2, or vice versa.

In a typewriting machine of the well-known Underwood type, the stationary guide 13, and the feed-roller mechanism together with the other guide 14, would be mounted on the frame of the machine at opposite ends respectively of the upper front horizontal member 43 of the frame which supports the usual scale 44, this member 43 (or the scale 44 carried by it) serving conveniently as a table or intermediate support to prevent the tape 11 from sagging. Obviously, in the case of languages or codes which are read from left to right, the stationary guide 13 would be mounted at the right-hand side of the machine and the feed-roller mechanism at the left-hand side as in the drawings. The supports for both these parts of the apparatus of the present invention may be integral with the frame 45 of the machine, or may be so formed as to be adapted for attachment to an existing machine. In the latter case the bearings for the rotary parts at the left-hand side, namely, the driving feed-roller 16, the ratchet wheel 25, and the gear wheels 41, 42, where such are em- 130

ployed, as well as the guide 14, the support for the spring-pressed feed roller 15, and the bracket 36 or 40, may conveniently be all formed upon a single bracket constituted by a casting or stamping 46 (Figs. 1 to 4) or 47 (Fig. 5) adapted to be fixed, along with the several parts carried by it, to the frame of the machine, thus saving considerable trouble in fitting. If necessary, the intermediate support for the tape between the two guides 13 and 14 may be provided as an adjunct in cases where no existing member of the frame can be conveniently utilized for the purpose.

15 The feed roller 15 is of small diameter relatively to the driving feed roller 16, and its axis 48 is carried by a pair of arms 49 each fixed to a section of a rock shaft 50. A spring 57 presses the roller 15 against the web 11 and the latter against the roller 16; the arms 49 serving as supplementary guides for the tape 11 which passes between them. The stationary guide 14 is shown as formed by a slot in the bracket 46 or 47, 20 and is parallel to the axes of the rollers 15 and 16, whereas the guide 13 (see Fig. 1) is canted toward the front of the machine to cause the tape to be presented conveniently for inspection by the typist.

25 30 In order to permit ready adjustment of the length of the connecting rod 22, it may be made in sections whereof one (preferably the lower one as in Fig. 4) is tubular, the lower part of the upper section being 35 slidable within the lower section and secured in adjusted position, a set-screw 52 passing through a collar 53 on the lower section.

35 The periphery of the driving feed roller 40 16 is preferably provided with a covering 54 of rubber or other material adapted to exercise a secure frictional grip upon the tape, and the periphery of the other feed roller 15 may have a similar coating 55.

45 Variations may be resorted to within the scope of the invention, and portions of the improvements may be used without others.

Having thus described my invention, I claim:

50 1. The combination with a machine for use in transcribing or copying from a strip or tape, of means extending across the machine for supporting the strip or tape containing copy in convenient position to be 55 viewed by the operator while operating said machine, and means operated by the foot of the operator for feeding the copy at will over said support at intervals corresponding in frequency to all movements 60 of the foot to present continuously to the view of the operator the portion of the copy which is being transcribed, and leaving the hands of the operator free for uninterrupted manipulation of the machine.

65 2. The combination with a machine for

transcribing copy from a strip or tape, said machine comprising a keyboard employing both hands of the operator, of a support extending across the machine for the web or tape containing copy, feed rolls one of 70 large diameter and provided with a friction surface, and the other of small diameter and swinging for imparting a forward movement to said strip or tape, a foot pedal, and means operated thereby for imparting a rotation to the feed rolls at the will of the operator to enable the copy to be advanced at the rate it is being transcribed, while leaving the hands of the operator free for uninterrupted manipulation 75 of the keyboard.

3. The combination with a machine for transcribing or copying from a web or tape, of guiding means for the tape containing the copy, feed rolls by which the tape is 80 fed, pawl and ratchet mechanism for driving one of said rolls to feed the tape, multiplying gear between the ratchet mechanism and the feed rolls, and a foot pedal for rapidly operating said mechanism in 85 multiplied response to downward pedal movements, and thereby feeding the web at intervals required to present continuously to the view of the operator the portion of the copy which is being transcribed, while 90 leaving the operator's hands free to uninterruptedly operate the machine.

4. The combination with a typewriting machine, of means for supporting and guiding across the machine a tape or web containing copy in convenient view of the operator while operating the machine, feed rolls between which said web or tape is fed, a ratchet wheel to drive said rolls, pawls co-operating with the ratchet wheel, a foot 100 pedal, and operating connections between said pedal and said pawls for driving the ratchet wheel by one of the pawls when the pedal is moved in one direction and for driving the ratchet wheel by the other pawl 105 when the pedal is moved in the opposite direction, thereby feeding the copy forward when the pedal is moved in either direction, permitting the copy to be advanced at the rate it is being transcribed, and leaving 110 the hands of the operator free for uninterrupted operation of the machine.

5. The combination with a machine for transcribing copy, of means for supporting and guiding a tape containing copy, feeding means for the tape, a ratchet wheel connected to drive said feeding means, pawls co-operating with the ratchet wheel, a foot pedal, and connections between said pedal and said pawls for driving the ratchet 115 wheel during the movement of the pedal in both directions, and thereby feeding the copy forward when the pedal is moved in either direction, permitting the copy to be advanced at the rate it is being transcribed, 120 125 130

- and leaving the hands of the operator free for uninterrupted operation of the machine.
6. In combination with a machine for transcribing copy from a web or tape, mechanism for feeding said web or tape comprising a ratchet wheel, arms pivoted concentric with said wheel, pawls carried by said arms to rotate said wheel, a reciprocating rod, links connecting said arms to said rod and located at opposite sides of the axis of said wheel, a lever to reciprocate said rod, and thereby impart a rotation to said wheel when the rod is moved in one direction and when the rod is returned to impart a further rotation to the wheel in the same direction, means driven by said ratchet wheel for feeding the tape containing the copy to be transcribed, a foot pedal for reciprocating said rod, and means to return the pedal after each operation in one direction by the foot of the operator, whereby the tape may be fed forward by a movement of the pedal in either direction, thereby enabling the operator by a single movement of the foot in either direction to feed the web forward at will at the rate the copy is being transcribed, while leaving the hands of the operator free for uninterruptedly operating the machine.
7. The combination with a typewriting machine, of guides located at opposite sides of the machine frame through which a web or tape containing copy is adapted to be fed, feed rolls supported on the machine frame beyond the guides for advancing the tape in the opposite direction from that in which the copy is readable thereon, a ratchet wheel to drive said rolls, pawls each operable to drive the ratchet wheel in the same direction, and a foot pedal for driving the ratchet wheel through one pawl when the pedal is depressed, and driving the ratchet wheel through the other pawl when the pedal is returned, whereby the copy may be advanced by the operator at intervals of a frequency corresponding to the rate at which the copy is being transcribed, and at the same time permitting the hands of the operator to be uninterruptedly employed in operating the machine.
8. The combination with a typewriting machine, of a support extending across the front of the machine, means for driving a tape or strip containing copy over said support in front of the eyes of the operator, a guide for said tape on one side of the machine, a guide carrying a feeding roller on the other side of said machine, a second feeding roller having a friction surface co-operating with the first-named roller, a foot pedal, and means acting with said foot pedal for multiplying the effect of pedal oscillations for feeding the tape over said support whereby the operator may feed the tape at will and practically continuously by movements of the foot while all the fingers are engaged in manipulating the keyboard.
9. In a typewriting machine, the combination of a holder for a copy tape or strip comprising guides at opposite sides of the machine frame to conduct the tape or strip across the front thereof, a receiving wheel having frictional feeding means, a ratchet to operate said receiving wheel, pawls to alternately actuate said ratchet, and pedal-operated spring returning means to successively actuate said pawls at each operation of said pedal means, whereby the tape or strip may be advanced from time to time as new lengths thereof are required to be brought to view, independently of manipulation.

JOHN JOSEPH COOPER.
